UNITED STATES PATENT OFFICE.

PETER J. MCGUIRE, OF BLAIRSVILLE, PENNSYLVANIA, ASSIGNOR TO THE CHAMPION SANITARY ENAMEL WARE CO., A CORPORATION OF PENNSYLVANIA.

MOLDING-FLASK.

SPECIFICATION forming part of Letters Patent No. 721,726, dated March 3, 1903.

Application filed January 31, 1902. Serial No. 91,951. (No model.)

To all whom it may concern:

Be it known that I, PETER J. MCGUIRE, a citizen of the United States, residing at Blairstown, in the county of Indiana and State of Pennsylvania, have invented a new and useful Improvement in Molding-Flasks, of which improvement the following is a specification.

This invention relates to certain new and useful improvements in molding-flasks, relating particularly to flasks for molding bathtubs.

The object of my invention is first to provide a flask structure for the above-mentioned purpose wherein but two flasks are employed, thereby considerably lessening the labor.

A second object of my invention is to provide means whereby accurate registration of the two flasks or mold parts is made and maintained when brought together.

Other novel features reside in the construction and arrangement of parts as hereinafter set forth.

In the accompanying drawings I have illustrated my improvements in various ways, in which—

Figure I is a plan view of the flasks as they would appear when set up for casting. Fig. II is a side view of the same. Fig. III is an end view of the same. Fig. IV is a transverse sectional view through the same on the line X X of Fig. I.

Further reference to said drawings for a detailed description of said views the numeral 1 designates the "drag-flask," consisting of an open frame having formed thereabout the flanges 2 and 3 and upon the ends thereof the trunnions 4, said trunnions being provided for convenience in handling said flask. Upon the flanges of said flask are formed the inclined ways or ribs 6 and 7, the upper flange being also provided with vertical pins 5. The ends and sides of said flask are provided with outwardly-extended guide boxes or receptacles 8, which boxes are provided at their side walls with moderately tight-fitting contact-screws 9. This drag-flask after being "rammed up" with sand to form the mold portion 10 is previous to being "rolled over" fitted with a bottom board 11, which board is

secured thereto by clamps 12, engaging over the inclined ways or ribs 7 of the flask and similar ribs 13 upon the under side of said board.

The "cope-flask" 14 consists of an open frame of considerable depth, tapering upwardly toward the center and having formed thereabout the flanges 15 and 16, said flask also having formed at its ends the trunnions 17. Upon the flanges of said flask are formed the inclined ways or ribs 18 and 19, of the same character as those upon the drag-flask, the lower ribs being positioned to coincide with those of said drag-flask when brought together, so that they may be firmly secured to one another by clamps 20, said lower flange being also provided with openings of such diameter as to freely engage over the pins 5 of the drag-flask and permit plenty of play therebetween. To the flange 16 of said cope-flask, at the ends and sides thereof, are secured the tapering tongues or guide members 21, which are adapted to go between and engage the screws 9 of the receptacles upon the drag-flask when brought together. Frames 22, 23, and 24 having flanged ends to engage upon the upper flanged portion of the cope-flask are provided, the sides of which form the flask-bars 22, 23, and 24 to extend down into said flask or mold therein, said frames being provided with inclined ways or ribs 25 at their ends, so that the same may be firmly secured to the flask by clamps 26. In this flask structure the pins 5 upon the one flask and the openings in the other to engage thereover are not depended upon to bring about proper fitting of the two when brought together, but they do perform the functions of auxiliaries to the main guides to more quickly and easily bring about the closure position between the main guides.

The main guides herein referred to are admirably adapted for bringing about accurate matching or registration of the two flasks or mold parts when brought together, which is a special feature in the manufacture of bathtubs, as the least perceptible play between the guide members will, owing to the thinness of metal and the difference in angularity and curvature thereof at various points,

result in unequal expansion and contraction and possible loss of said tub. In this structure of guide the one member, 21, being tapered upon its opposite engaging sides and 5 the other member, 8, being provided with adjustable screws to engage the tapered surfaces of said first member when the two flasks or molds are brought together a perfect tight contact between the members is 10 made, and as the flasks are provided at both ends and sides with these guides either longitudinal or lateral displacement of one mold part or flask in relation to the other is effectively prevented. Furthermore, by means of 15 the screws 9 adjustment of one flask or mold part in respect to the other may be made, and the proper position being once determined may be maintained.

Heretofore it has been customary to mold 20 bath-tubs in a three-part flask, the central flask forming the "cheek;" but in this structure only two flasks are employed—namely, cope and drag, with detachable frames forming the bars for the latter flask.

25 In practice the frames are placed upon and secured to the cope-flask after the latter has been rammed up a sufficient distance to cover the pattern, the sand forming the remaining portion of the mold being then rammed about 30 said bars.

By casting the inclined ribs upon the flasks and the detachable frames the same may easily and quickly be secured together by the clamps and in like manner the bottom board 35 attached.

By the use of the two-part flask structure herein described I am enabled to greatly reduce the labor and cost of manufacturing cast bath-tubs. Furthermore, the tubs cast 40 will be perfectly smooth throughout their entire surface, which is not attainable where a cheek is employed.

Having thus fully shown and described my invention, what I claim as new, and desire to 45 secure by Letters Patent, is—

1. In a plural-part flask adapted for molding bath-tubs, the combination with the member designed to confine the entire mold part for the exterior of the tub thereof of removable sand-retainers comprehending two or 50 more cross-bars having outward extensions integral therewith by a cross-piece adapted when the mold has been partly rammed up to be inserted in said flask and suspended 55 therein by direct engagement of said extensions upon the upper opposite edges proper of said flask.

2. In a plural-part flask, the combination therewith of adjustable registering members 60 arranged at the ends and sides of their meeting edges whereby the registering position of one flask member upon the other may be adjustably varied longitudinally by said side members without disturbing those at the ends 65 or laterally by said end members without disturbing those at the sides, and removable internal sand-retainers for the cope member

comprehending two or more connecting cross-bars having outward extensions adapted to engage upon the upper edges of said cope 70 member and support the bars therein whereby the same may readily be removed to permit that portion of said flask extending below said bars being rammed up.

3. A two-part flask for molding bath-tubs, 75 comprising a cope and a drag flask member each having integral inclined clamping-strips at their meeting and top and bottom edges, a plurality of integral cross-bars having inclined clamping-strip extensions at their ends 80 to engage upon and register with those at the top of the cope-flask, and registerable adjusting members arranged upon the sides and ends of said flasks at their meeting edges adapted to laterally and longitudinally adjust 85 the position of one flask with the other and when adjusted maintain the same in such position against displacement in either of said directions, said registering members comprehending vertically-extended wedge-shaped 90 tongues carried by one flask and set-screws carried by the other at like points to engage opposite tapered sides of said tongues.

4. A two-part flask for molding bath-tubs, 95 comprising a cope and a drag flask member each having integral inclined clamping-strips at their meeting and top and bottom edges, a plurality of integral cross-bars having inclined clamping-strip extensions at their ends 100 to engage upon and register with those at the top of the cope-flask, guide-pins projecting from the meeting edge of one flask to enter openings in the other, and registerable adjusting members arranged upon the sides and ends of said flasks at their meeting edges 105 adapted to laterally and longitudinally adjust the position of one flask with the other and when adjusted maintain the same in such position against displacement in either of said directions, said registering members comprehending vertically-extended wedge-shaped 110 tongues carried by one flask and set-screws carried by the other at like points to engage opposite tapered sides of said tongues.

5. A two-part flask for molding bath-tubs, 115 comprising a cope and a drag flask member each having integral inclined clamping-strips at their meeting and top and bottom edges, a plurality of integral cross-bars having inclined clamping-strip extensions at their ends 120 to engage upon and register with those at the top of the cope-flask, guide-pins projecting from the meeting edge of one flask to enter openings in the other, registerable adjusting members arranged upon the sides and ends of 125 said flasks at their meeting edges adapted to laterally and longitudinally adjust the position of one flask with the other and when adjusted maintain the same in such position against displacement in either of said directions, a bottom board carrying inclined clamping-strips to register with those at the bottom edge of the drag-flask, and clamps having their jaws inclined to correspond with and en- 130

gage the clamp-strips at the top bottom and meeting edges of said parts, said adjusting members comprehending vertically-extended wedge-shaped tongues carried by one flask and set-screws carried by the other at like points to engage opposite tapered sides of said tongues.

In testimony whereof I have hereunto signed my name in the presence of two subscribing witnesses.

PETER J. McGUIRE.
